UNITED STATES PATENT OFFICE.

WILLIAM B. LAWRENCE, OF COLUMBUS, OHIO.

DESIGN FOR A FABRIC FOR PINCUSHIONS.

No. 38,479.

Specification for Design.

Patented March 12, 1907.

Application filed December 15, 1906. Serial No. 343,060. Term of patent 3½ years.

To all whom it may concern:

Be it known that I, WILLIAM B. LAWRENCE, a citizen of the United States, residing at Columbus, in the county of Franklin and State of Ohio, have invented a new, original, and ornamental Design for a Fabric for a Pincushion, of which the following is a specification, reference being had to the accompanying drawing, forming part thereof.

The view illustrates the design.

I claim—

The ornamental design for a fabric for a pincushion as shown.

WILLIAM B. LAWRENCE.
